(57) **CLAIM**

We claim the ornamental design for a pressure sensor with pivotable antenna, as shown and described.

DESCRIPTION

FIG. 1 is a top-front-right-side perspective view of our new design for a pressure sensor with a pivotable antenna shown in a first configuration of use;

FIG. 2 is the perspective view of FIG. 1, shown in a second configuration of use;

FIG. 3 is a front view thereof;

FIG. 4 is a back view thereof;

FIG. 5 is a left side view thereof;

FIG. 6 is an elevated right side view thereof;

FIG. 7 is a top plan view thereof;

FIG. 8 is a bottom plan view thereof; and,

FIG. 9 is an enlarged partial view of the area shown circled in FIG. 2.

The dash-dot broken lines shown in the views are for the purpose of illustrating portions of the pressure sensor with pivotable antenna that form no part of the claimed design.
